ATTORNEY

UNITED STATES PATENT OFFICE

ERNEST L. WALRATH, OF BEND, OREGON

GOLF TEE POSITIONING DEVICE

Application filed May 18, 1931. Serial No. 538,315.

This invention relates to a golf tee positioning device and has for the primary object the provision of a device of the above stated character especially adaptable for holding a golf tee and inserting the same into the ground to a predetermined depth and automatically releasing the tee when positioned, that a ball may be placed thereon and driven in the usual way and which will support the ball at approximately the same height from the ground each time used, thereby assuring a more accurate drive by the player than obtainable from a tee inserted in the ground by hand and where no actual gage may be had for the head of the tee relative to the ground each time the tee is positioned in the ground.

Another object of this invention is the provision of means for releasing the tee holding means after the tee has been used and replaced in said holding means whereby the tee may be safely kept and ready for use when the next drive is to be made by the player.

Another object of this invention is the provision of a device of the above stated character which may be in the form of an attachment to be applied to the end of a golf club or to be applied to any suitable handle and carried by the player in the golf bag with other clubs.

A further object of this invention is the provision of a golf tee positioning device which will be simple, durable and efficient, and which may be manufactured and sold at a comparatively low cost.

With these and other objects in view as will become more apparent as the description proceeds, the invention consists in certain novel features of construction, combination and arrangement of parts as will be herein-after more fully described and claimed.

For a complete understanding of my invention, reference is to be had to the following description and accompanying drawing, in which

Figure 1 is a vertical sectional view illustrating a golf tee positioning device constructed in accordance with my invention.

Figure 2 is a similar view showing the de-

vice in the act of positioning the tee in the ground and automatically releasing the tee.

Figure 3 is a view similar to Figure 1 showing in elevation the sleeve for opening the tee holding dogs when the tee has been inserted in the ground as shown in Figure 2.

Figure 4 is a sectional view similar to Figure 3 except that the device is in a position for inserting the tee in the ground and prior to removing the same from the tee.

Figure 5 is a detail view illustrating a manually controlled release for the tee gripping dogs to be actuated after a tee has been used and replaced in the device.

Figure 6 is a perspective view illustrating a locking means for the dogs, and

Figure 7 is a perspective view illustrating one of the dogs.

Referring in detail to the drawing the numeral 1 indicates a cylinder or casing which has one end closed by an integral wall 2 provided with a centrally arranged opening 3 surrounded by a sleeve 4 forming an integral part of the bottom 2 and providing a passageway for a tee 5 of the usual construction. The other end of the casing or cylinder 1 has located therein a head 6 and is limited from moving outwardly of the casing 1 by the inturned edges 7. The head 6 is slidable in the casing 1 and is provided with an annular wall 8 carrying a flange 9 forming a seat for one end of a coiled spring 10 which also rests on the bottom wall 2. The action of the spring 10 is normally to urge the head toward the flange 7.

A dog supporting sleeve 11 has one end closed and apertured to receive a fastener 12 which also extends through the head 6 for attachment with the handle 13. The handle 13 may be of any desired construction and if desired the device may be attached to the end of an ordinary golf club by the fastener 12. The sleeve 11 carried by the head 6 is slidably received within the sleeve 4 and receives therein the head of the tee 5. A plate 14 is located in the sleeve 11 to provide a stop for limiting the movement of the tee into the sleeve 11. Substantial L-shaped dogs 15 are pivoted in the sleeve 11 as shown at 16 and the dogs operate

100

through slots 17 formed in the sleeve and engage about the head of the tee as clearly shown in Figure 1 under the influence of a coiled spring 18 to retain the tee in the sleeve 5 11 and against the plate 14.

The sleeve 4 is provided with oppositely disposed slots 19 that align with the slots 17 and have portions thereof enlarged to form shoulders 20 adapted to engage shoulders 21 formed on the dogs 15 for the purpose of spreading or releasing the dogs from engagement with the head of the tee when the device is positioned as shown in Figure 2 and in the act of inserting the tee in the ground. 10 Pivot pins 22 are carried by the sleeve 11 and extend through the slots 19 and have pivoted thereto latch arms 23 having cut out portions 24 to provide shoulders 25 adapted to engage the dogs or the shoulders 21 thereof for locking said dogs in a spread position as shown in Figure 2 and against the action of the spring 18.

The latch arms 23 are connected at their free ends by a substantially U-shaped member 26 provided with an apertured ear 27 to which a finger piece 28 is connected and which extends through an opening 29 in the head 6 and also through a slot 30 in the casing or cylinder 1. A leaf spring 31 is connected to the head 6 at one end and the opposite end connected to the U-shaped member 26 for normally positioning the latch arms 23 that their shoulders 25 will engage the dogs when the latter are spread during the use of the device and retain said dogs in the stated position that the device may be removed from the tee after the insertion of the tee in the ground. After the player has finished using the tee, the same is manually withdrawn from the ground and inserted into the device and the finger piece 28 pressed which releases the dogs permitting them to again grip the tee and retain the latter in the device ready for further use, when desired.

In operation, the player positions the device against the ground as shown in Figure 1 and by exerting pressure in a downward direction on the handle, the tee 5 will be inserted in the ground to a predetermined depth and simultaneously the dogs will be spread or moved apart and automatically latched in this position, freeing the tee and the player then lifts the device from the tee. The player places the ball on the tee in the usual way and after the drive has been made, the tee is extracted from the ground and again placed in the device and the player presses upon the finger piece 28 which releases the dogs that they again grip the head 60 of the tee under the influence of the spring 18.

Therefore it will be seen that a device has been provided whereby a tee may be easily and quickly inserted in the ground to a predetermined depth that the ball supported by the tee will in every instance be approximate-

ly the same distance from the ground, and further it is to be noted that the device will maintain the tee ready for use at all times and protected against injury or loss.

While I have shown and described the preferred embodiment of my invention it will be understood that minor changes in construction, combination and arrangement of parts may be made without departing from the spirit and scope as claimed.

Having thus described my invention, what I claim is:

1. A golf tee positioning device comprising a handle, a head secured to the handle, a casing slidable on the head and having an opening, tension means between the head and casing, a sleeve secured to the head in alignment with said opening to receive a tee, gripping means in said sleeve to engage the tee and retain the latter within the sleeve, means carried by the casing to disengage the gripping means from the tee when the latter has been inserted in the ground by pressure placed on the handle and with the casing in engagement with the ground, and means carried by the sleeve for releasing the gripping means from the last named position after the tee has been again inserted in the sleeve.

2. A golf tee positioning device comprising a handle, a head secured to the handle, a casing slidable on the head and having an opening, tension means between the head and casing, a sleeve secured to the head and receiving a tee, spring pressed pivoted dogs in the sleeve for engaging the tee to retain the latter in the sleeve, and means carried by the casing to disengage the dogs from the tee when pressure has been placed on the handle with the casing in engagement with the ground for positioning the tee in the ground at a predetermined depth, means for locking the dogs in the last named position, and means carried by the sleeve for releasing the dogs from said last named position when the tee is again inserted in the sleeve.

3. A golf tee positioning device comprising a handle, a head carried by the handle, a casing slidable on the head and having an opening, a sleeve carried by the head and in alignment with the opening to receive a tee, pivoted dogs in the sleeve, tension means engaging said dogs to normally urge the latter in engagement with the tee, a member carried by the casing to disengage the dogs from the tee when pressure is placed on the handle with the casing in engagement with the ground for positioning the tee in the ground to a predetermined depth, locking means carried by said member and holding the dogs in tee releasing position, and means connected to said locking means to disengage the latter from the dogs when a tee has been again inserted in the sleeve.

4. A golf tee positioning device comprising a handle, a head secured to the handle, a cas-

ing slidable on the head and having an opening, tension means between the head and having an opening, tension means between the head and casing, a sleeve secured to the head
5 and in alinement with said opening to receive a golf tee, dogs pivoted in said sleeve to engage the tee, tension means normally urging the dogs in engagement with the tee, a member carried by the casing to disengage the
10 dogs from the tee when pressure has been placed on the handle and with the casing in engagement with the ground for inserting the tee in the ground to a predetermined depth, latch arms pivoted to said sleeve, tension
15 means bearing against said latch arms for urging the latter in engagement with the dogs when in tee releasing position, and a finger piece connected to said latch arms to disengage the latter from the dogs when a
20 tee has been again inserted in the sleeve.

In testimony whereof I affix my signature.
ERNEST L. WALRATH.
